2,420,176

CATHODE-RAY TUBE WITH INCLINED
TARGET

George Ross Kilgore, Princeton, N. J., assignor to
Radio Corporation of America, a corporation
of Delaware

Original application May 28, 1941, Serial No.
395,621, now Patent No. 2,372,282, dated March
27, 1945. Divided and this application June 29,
1944, Serial No. 542,716

3 Claims. (Cl. 315—17)

1

My invention relates to electron discharge devices, more particularly to such devices suitable for use at high frequencies and employing a beam of electrons and deflecting means for said beam to produce a modulated output current.

The present application is a division of my copending application, Serial No. 395,621, filed May 28, 1941, issued March 27, 1945, as Patent 2,372,282, and assigned to the same assignee as the present application.

In conventional devices employing a beam and utilizing deflection means, the electron stream is modulated by deflecting the beam past an aperture in an apertured electrode. Such a device is inefficient insofar as the intercepted current which becomes waste current is concerned, and requires the use of an additional electrode, that is the apertured electrode. This electrode adds electrode capacity to the tube, which at the higher frequencies is undesirable since this further affects the efficiency of the tube as well as increases the number of leakage paths between the various electrode leads.

Hence, it is an object of my invention to provide an electron discharge device particularly useful at high frequencies and employing a beam and deflecting means for the beam for producing a modulated output current.

More specifically, it is an object of my invention to provide such an electron discharge device in which the transit time of the electrons, the shape and position of the electrodes and the frequency of the controlling voltage or voltages are such that the action of the deflection means produces a modulated current in the output of the electron discharge device.

The novel features which I believe to be characteristic of my invention are set forth with particularity in the appended claims, but the invention itself will best be understood by reference to the following description taken in connection with the accompanying drawing in which Figure 1 is a diagram explaining the theory of operation of an electron discharge device made according to my invention, Figure 2 represents the output current of a device made according to my invention, Figure 3 is a diagrammatic longitudinal section of an electron discharge device and circuit made according to my invention, Figure 4 is a modification of the device shown in Figure 3 and its associated circuit, and Figure 5 shows a tube corresponding to the tube in Figure 4 but used in the push-pull output circuit arrangement.

Referring to the drawing in Figure 1, the point Q represents an electron source for providing a

2

beam of electrons directed between a pair of deflecting electrodes D₁ and D₂. These electrons are directed toward an anode or output electrode P having positioned in front of it a screen S. As the beam is deflected, the path length of the electrons from Q to plate P is varied and the transit time of the electrons will vary accordingly. If B₁ and B₂ represent the maximum excursion of the beam and the difference in transit time along the paths QB₁ and QB₂ is made to equal one-half the period of the applied alternating control voltage on plates D₁, D₂, then on the upward swing of the beam, an electron will reach B₁ at the same instant an electron which left the source of electrons Q one-half cycle earlier reaches B₂. Thus, it is possible by the application of proper biasing voltages and proper controlling voltage to have all the electrons which pass through the same plane T—T' on the upward swing reach the output electrode P at approximately the same instant of time.

On the downward deflection, however, the electrons will reach the plate P at wider and wider intervals. As a result the electron current reaching the output electrode P will have a wave shape something like that shown in Figure 2. Thus, with a uniform flow of electrons from the source Q a modulated current is produced in the output electrode P. The screen S is introduced close to the plate P so that the high frequency current induced in the output electrode P will not be reduced appreciably by transit time effects.

The incorporation of an electrode structure corresponding to that shown in Figure 1 in an electron discharge device, and its associated circuit, is shown in Figure 3. An indirectly heated cathode 11 provides a source of electrons which is formed into a beam by means of the longitudinal cylindrical electrode system having the apertured inserts 13 and 14, the apertures being aligned to provide beam formation. The beam is directed between a pair of deflecting electrodes 15 and 16 toward output electrode 17 inclined with respect to the beam, a screen electrode being provided in front of the output electrode. The cylindrical electrode system 12 may surround the output electrode and screen to completely screen it from output interference, if so desired. Input circuit 20 is connected between the deflecting electrodes 15 and 16 and a positive point on the voltage source 22, the output 21 being connected between the voltage source 22 and the output electrode 17, by-passing of the high frequency current of the screen being accomplished by means of high frequency condenser 23 which also per-

mits a different D.-C. voltage to be applied to the anode and the screen. The frequency of the voltage applied to the input circuit 20 and biasing voltages applied to the other electrodes are such that the velocity of the electrons and the deflection caused by the controlling voltage makes the electron transit time difference between the maximum points of swing equal to one-half the period of the frequency of the applied voltage to the deflecting electrodes 15 and 16, in this way obtaining an output such as shown in Figure 2.

In the modification shown in Figure 4 a special case is shown in which a pair of output electrodes are displaced a distance equal to a multiple of one-half period of the transit time of an electron during half a period. Here again cathode 26 supplies electrons which are formed into a beam by an electrode system which comprises cylinder 27 and apertured electrodes 28 and 29. The beam of electrons passes between deflecting electrodes 30-31 to output electrode elements 32 and 34 screened by means of screen electrodes 33 and 35. Electrode 33 may be on both sides of electrode element 32 to completely shield it from the electron stream when it passes to electrode 34. The input voltage is applied by means of input circuit 36 to the deflecting electrodes 30-31, and output circuit 37 is connected to the electrode 34 electrically connected to electrode 32 by means of conductor 38. The spacing between electrodes 32 and 34 is such that the transit time of electrons between the two electrodes 32 and 34 is a multiple of one-half period of the applied controlling voltage. In the case shown the transit time τ is made equal to one period T . Thus the current pulses reach P_1 and P_2 in phase. The result of this is a current having twice the amplitude flowing for a half period of the applied input voltage.

In Figure 5 the output electrodes 32 and 34 are connected to opposite sides of a push-pull output transformer. Inasmuch as the transit time space between the two electrodes is made equal to one-half period, the current flowing to each output electrode is in the proper phase relationship to bring about excitation of the output transformer 37.

While I have indicated the preferred embodiments of my invention of which I am now aware and have also indicated only one specific application for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim as new is:

1. An electron discharge device having a cathode for supplying electrons and means for forming electrons from said cathode into a directed beam, an output electrode for receiving said electrons and a pair of deflecting electrodes between which said beam is directed to said output electrode, said output electrode including a member having a plane surface positioned at an angle to the path of said beam, said beam forming means comprising a tubular member surrounding said deflecting electrodes and said output electrode and having a transverse element closing one end of said tubular member adjacent said cathode and provided with an aperture registering with said cathode and the other end of said tubular member being closed by a trans-

verse element, whereby said deflecting electrodes and output electrode are completely shielded, an input circuit connected to said deflecting electrodes for applying an alternating controlling voltage to said deflecting electrodes, an output circuit connected to said output electrode, a source of voltage, means connected between said source of voltage and said electron discharge device for providing biasing voltages, the frequency of said controlling voltage being such that the difference in transit time between the output electrode surface nearest said deflecting electrodes and the part of said output electrode most distant from said deflecting electrodes is of the order of one-half period of oscillation of the controlling voltage.

2. An electron discharge device having a cathode for supplying electrons and means for forming electrons from said cathode into a directed beam, an output electrode for receiving said electrons and a pair of deflecting electrodes between which said beam is directed to said output electrode, said output electrode including a member having a plane surface positioned at an angle to the path of said beam, said beam forming means comprising a tubular member surrounding said deflecting electrodes and said output electrode and having a transverse element closing one end of said tubular member adjacent said cathode and provided with an aperture registering with said cathode, a screen electrode between said deflecting electrodes and said output electrode, an input circuit connected to said deflecting electrodes for applying an alternating controlling voltage to said deflecting electrodes, an output circuit for said device, a source of voltage, means connected between said source of voltage and said electron discharge device for providing biasing voltages, the frequency of said controlling voltage being such that the difference in transit time between the output electrode surface nearest said deflecting electrodes and the part of said output electrode most distant from said deflecting electrodes is of the order of one-half period of oscillation of the controlling voltage.

3. An electron discharge device having a cathode for supplying electrons and means for forming electrons from said cathode into a directed beam, an output electrode for receiving said electrons and a pair of deflecting electrodes between which said beam is directed to said output electrode, said output electrode including a member having a plane surface positioned at an angle to the path of said beam, a screen electrode positioned adjacent the output electrode, said beam forming means comprising a tubular member surrounding said deflecting electrodes and said output electrode and having a first transverse element closing one end of said tubular member adjacent said cathode and provided with an aperture registering with said cathode, and the other end of said tubular member being closed by a second transverse element, whereby said deflecting electrodes and output electrode are completely shielded, and a third transverse element between said first transverse element and said deflecting electrode and having an aperture registering with the aperture in the first transverse element, an input circuit connected to said deflecting electrodes for applying an alternating controlling voltage to said deflecting electrodes, an output circuit connected to said output electrode, a source of voltage for providing biasing voltages for said electron discharge device, the

frequency of said controlling voltage being such that the difference in transit time between the output electrode surface nearest said deflecting electrodes and the part of said output electrode most distant from said deflecting electrodes is of the order of one-half period of oscillation of the controlling voltage.
